(David G. Galbraith).

UNITED STATES PATENT OFFICE.

DAVID G. GALBRAITH, OF MINERAL WELLS, TEXAS, ASSIGNOR TO NANNIE L. GALBRAITH, OF MINERAL WELLS, TEXAS.

DEVICE FOR TYING AND UNTYING PACKAGES.

1,054,107.

Specification of Letters Patent. Patented Feb. 25, 1913.

Application filed October 1, 1908. Serial No. 455,703.

To all whom it may concern:

Be it known that I, DAVID G. GALBRAITH, of Mineral Wells, in the county of Palo Pinto, State of Texas, have invented a certain new and useful Improvement in Devices for Tying and Untying Packages; and I do hereby declare the following to be a full, clear, and exact description of the same, reference being had to the accompanying drawings, forming a part of this specification, and to the figures and letters of reference marked thereon.

This invention relates to devices for facilitating the application and removal of confining cords to packages, the objects of the invention being to provide a simple device with which the cord may be easily and quickly secured or released without undue wear on the cord.

20 A further object of the invention is to provide a device which may be used to secure the cord when passed either around the package in one direction or in two directions, all as will hereinafter appear.

25 In the accompanying drawings: Figure 1 is a perspective view of a package with a confining cord thereon held by a device embodying the present improvements. Fig. 2 is a plan view of a package with the confining cord passed around the same in one direction and held by a securing device embodying the present invention.

35 The securing device of the present invention is bent up from a single piece of wire the two ends being of similar conformation but reversed with relation to each other while the central part of the wire forms a hook in which a bight of the cord may be drawn taut before being secured.

40 As shown in the drawings the wire is bent rather sharply at the center A to form a hook recess c. Each arm is bent back on itself as at g to form cord pinching and holding slots b and finally the ends are bent outwardly and turned back into proximity to the extremities of the cord holding slots, thereby forming guides and handles d. The handles d diverge from the parts i, i, of the arms a sufficient distance from the bend A 45 to form converging guides for the cord which latter will be directed into the holding slots without the necessity of accurate placing by the person tying the package.

50 In making use of the securing device one end of the cord is drawn into one of the

securing slots b where it will be firmly held. The thumb or finger is then placed on the handle adjacent the slot in which the end of the string is secured and the string passed around the package, hooked 60 into the bend A and drawn taut with a pulley action. The cord is next passed around the package the other way and the end drawn tightly into the other holding slot as shown clearly in Fig. 1. 65

As shown in Fig. 2 of the drawing the cord is passed around the package in one direction only but a doubled loop of cord is used. To apply the cord in this use of the device, one end of the cord is secured 70 and the cord passed around the package as before and drawn tight, then the free end is brought back in the same direction and secured in the other slot of the fastener. If desired to lock the cord with greater security the free ends may be doubled back 75 and drawn down into the slots as shown in Fig. 2, when it will be found that the slight enlargement due to the bending of the cord shown at J will afford greatly increased resistance to any slipping of the cord.

Obviously the handle and guide portions of the fastener may be of any desired shape, round and angular forms being illustrated 85 in the drawings. The arms i—i form an acute angle—thus each arm will form the end of a hook of which the other arm is the shank and the cord may be drawn tight without liability of slipping off no 90 matter whether the tie be used right or left handed.

What I claim as new and desire to secure by Letters Patent, is:—

1. A securing device for package confining cords embodying a single length of wire having a central bend for a bight of the cord, the ends of the wire diverging at an acute angle whereby either will form the end of a hook and the other the shank, each end being bent back on itself to form a cord pinching and holding slot and beyond said slot diverging from the body of the wire to form guides for the cord the extremities of both ends being brought into proximity to the ends of the slots to form oppositely extending handles by which the device may be held in fastening a package, the said slots for the ends of the cord being arranged to lie in substantially the same 100 105 110

plane whereby the ends of the cord will both be held in a plane parallel with the surface of the package.

2. A securing device for package confining cords embodying a single length of wire having a central bend forming a hook for a bight of the cord, arms diverging at an acute angle from said bend, the said arms being doubled back on themselves to form 10 cord pinching and holding slots and thence extending in opposite directions intermediate the slots and central bend to form with the inner ends of the arms diverging guides for the cord and the extremities being bent

into proximity to the ends of the slots to 15 form oppositely extending handles by which the device may be held during the application of the cord to the package, the said slots for the ends of the cord being arranged to lie in substantially the same plane whereby 20 the ends of the cord will both be held in a plane parallel with the surface of the package.
